UNITED STATES PATENT OFFICE

2,607,946

COMBINED STOOL AND RETRACTABLE FOOTREST

Edward V. Price and Veronica E. Price,
Van Nuys, Calif.

Application July 16, 1946, Serial No. 683,875

9 Claims. (Cl. 15—265)

1

This invention relates to a stool; more particularly to a stool having a folding foot rest arranged optionally to provide shoe cleaning facilities.

It is an object of this invention to provide such a stool which is compact and readily portable, and which presents a pleasing appearance.

It is another object of this invention to provide a stool adapted to provide a seat in a conventional manner, and which optionally may provide means for supporting the user's foot in a raised position for facilitating cleaning or polishing the shoe.

It is another object of this invention to provide a stool having novel means arranged to fold within the stool, and which, when extended, forms a firm support for the user's foot.

It is another object of this invention to provide a stool having novel means for holding shoe cleaning equipment, such as brushes, dressings, polishes, and the like, within the stool, and which renders such articles readily accessible when the foot support is extended for use.

This invention possesses many other advantages, and has other objects which may be made more clearly apparent from a consideration of one embodiment of the invention. For this purpose there is shown a form in the drawings accompanying and forming part of the present specification. The form will now be described in detail illustrating the general principles of the invention; but it is to be understood that this detailed description is not to be taken in a limiting sense, since the scope of this invention is best defined by the appended claims.

In the drawings:

Figure 1 is an elevation of a stool incorporating the features of the invention;

Fig. 2 is a transverse section on an enlarged scale, taken as indicated by line 2—2 on Fig. 1;

Fig. 3 is a cross section, taken as indicated by line 3—3 on Fig. 2;

Figs. 4, 5 and 6 are detail sections, taken as indicated by correspondingly numbered lines on Fig. 7;

Fig. 7 is an elevation, partly in section, showing the foot support in extended position;

Fig. 8 is a top plan view of the foot support, taken as indicated by line 8—8 on Fig. 7; and

Fig. 9 is a section on an enlarged scale, taken

as indicated by line 9—9 on Fig. 7, part of the structure being broken away to reduce the size of the figure.

The stool comprises a seat forming member

1 supported at an appropriate height by a hollow supporting structure 2. A member 3 is arranged to extend from the structure 2 below the seat 1 and to provide a support for the foot of a person seated on the stool. In this way, the foot is positioned so that the shoe, or the like, thereon may be reached conveniently for cleaning and polishing. When not in use, the member 3 may be folded so as to be entirely within the supporting structure 2, reducing the space requirements of the device and permitting its use as a conventional stool.

Referring in detail to the stool, the supporting structure 2 comprises a pair of oppositely directed frusto-conical metallic wall sections 4 and 5, appropriately joined at their small ends as by having short cylindrical portions telescoped one within the other and spot welded (Fig. 5). The lower section 4 is closed at its lower end by a bottom plate 6, secured in a conventional manner. The upper end of the upper section 5 is closed by a convex head 7, the seat 1 being formed on the head 7. For this purpose, suitable upholstery stuffing, indicated by 8, is confined between the head 7 and a covering 9 of leather or other suitable material, such as fabric.

As clearly shown in Fig. 4, the section 5 is provided with an inwardly projecting bead 10 adjacent its upper end, the head 7 telescoping within the section 5 and engaging the bead 10. The covering 9 extends over the outside of the upper end of the section 5 and is clamped thereabout by an encircling band 11, secured to the section by screws 12 which also serve to secure the head 7, and are engaged by nuts 13 on the inside of the head.

The joint between the sections 4 and 5 is covered by a similar ornamental band 15, secured as by screws and nuts 16 and 17 (see Fig. 5). The lower end of the lower section 4 is also provided with an inwardly projecting bead 18, against which the bottom 6 is clamped by flanging over portions 19 of the lower edge of the section 4 (see Fig. 6). The bottom 6 has supporting buttons or feet 20 secured thereon.

The member 3, forming the foot support, is

mounted for swinging movement in a generally vertical direction in any convenient manner, as, for example, by a conventional hinge 23. One leaf 23-a of this hinge is secured to the bottom 6. The member 3 comprises a shoe-supporting sole plate 24, having a nearly perpendicular extension 25 to which the other hinge leaf 23-b is secured. An opening 26 is provided in the upper portion 5 of the support for permitting the support member 3 to be swung about its pivot 23 to a position in which the sole plate 24 extends from the structure or housing 2 (see Fig. 7). In the folded position of Fig. 2, the extension 25 rests on the bottom plate 6.

The outer end of the plate 24 is provided with means 27 to support the plate when the member 3 is in extended position. This means 27 carries a cover 28, closing the opening 26 when the member 3 is positioned within the structure 2. The support 21 comprises a back plate 29 substantially perpendicular to plate 24, and side pieces 30 and 31 joined by members 32 forming compartments 33 for shoe brushes, polishing cloths, shoe polish, and the like. As clearly shown in Fig. 7, these compartments 33 are readily accessible when the foot support 3 is in extended position. At the same time, accidental dislodgement of such articles is prevented by the upward inclination of the shelves 32.

The cover 28 is provided with a handle 35 which, as clearly shown in Figs. 3 and 9, extends beyond the sides of the cover and, by engaging the upper section 5 at the sides of opening 26, serves to limit inward movement of the member 3. By engaging the floor or other surface on which the stool rests, the handle 35 serves to support the member 3 when in extended position.

The elements 25 and 29, together with plate 24 form a structure that can either straddle the lower edge of opening 26 (Fig. 7), or else can be folded compactly into the stool (Fig. 2). This is effected by the provision of a pivot for the hinge 23 that is located substantially below the lower edge of opening 26.

The sole plate 24 has a plate 36 slidable thereon, and adapted to form an extension of the plate 24 (see Figs. 7 and 8). For this purpose, members 37 and 38 are provided on walls 30 and 31, forming grooves for accommodating the opposite edges of the extension plate 36. The plate 36 is freely slidable in these grooves, its inward movement being limited by a downward projection 36-a adapted to engage the outer end of the plate 24. The outward movement of plate 36 is limited by the engagement of upward projections 36-b with the inner ends of the groove-forming members 37 and 38. The extension plate 36 may be provided with a rubber tread 40. The plate 36 is thus capable of some adjustment for the accommodation of the user.

The inventors claim:

1. In a stool: means including a base and a wall extending upwardly therefrom forming an inclosure supporting a seat; there being an opening through the upper portion of said wall; a member adapted to be positioned to project through said opening for a substantial distance exteriorly of said wall in a generally horizontal direction to form a foot support, and when so positioned, having means rigidly connected to said member and adjacent its opposite ends and downwardly directed to form supports for said member, one of said means being within said inclosure, and spaced inwardly of said opening, said one of said means contacting said base, the

other of said means being outside said inclosure.

2. In a stool: means including a wall forming an inclosure supporting a seat, there being an opening in the upper portion of the wall; a member adapted to be positioned to project through said opening for a substantial distance exteriorly of said wall to form a foot support and having a downwardly directed supporting extension pivoted on said inclosure and below the opening, and downwardly extending support means rigidly connected to said member and outside said inclosure.

3. In a stool: means including a wall forming an inclosure supporting a seat, there being an opening in the upper portion of said wall; a member adapted optionally to extend through said opening to form a foot support and to be retracted beneath the seat; said member having an extension within said inclosure, pivotally secured to said inclosure forming means and spaced from said opening; means for supporting the outer end of said member when in extended position; and means carried by said supporting means for covering said opening completely when said member is in retracted position.

4. In a stool: means including a wall forming an inclosure supporting a seat, there being an opening in the upper portion of said wall; a member adapted optionally to extend through said opening to form a foot support, and to be retracted beneath the seat, said member having an extension within said inclosure, pivotally secured to the means that forms an inclosure; means for supporting the outer end of said member when in extended position; closure means carried by the support means for closing said opening when said member is in retracted position; means on said closure adapted to engage said wall adjacent said opening to limit inward movement of said member and to engage the ground when said member is extended.

5. In a stool: a support having a wall provided with an aperture; a seat on the top of the support; a generally U-shaped member movable through said aperture, said member having a central foot rest portion and spaced supporting legs secured to said central portion; means pivotally supporting one of said legs inside said support below said aperture, the other of said legs being rigidly mounted and disposable outside said wall to support said central portion when said central portion extends through said aperture.

6. In a stool: a support having a wall provided with an aperture; a seat on the top of the support; a generally U-shaped member movable through said aperture, said member having a central foot rest portion and spaced supporting legs rigidly secured to the ends of said central portion; means pivotally supporting one of said legs inside said support below said aperture, the other of said legs being disposable outside said wall to support said central portion when said central portion extends through said aperture.

7. In a stool: a support having a base and a wall extending upwardly from the base and provided with an aperture; a seat on the top of the support; a generally U-shaped member movable through said aperture, said member having a central foot rest portion and spaced supporting legs secured to said central portion; means pivotally supporting one of said legs on said base inside said support and below said aperture, the other of said legs being disposable outside said wall to support said central portion when said central portion extends through said aperture.

8. In a stool: a support having a wall provided with an aperture; a seat on the top of the support; a generally U-shaped member movable through said aperture, said member having a central foot rest portion and spaced supporting legs secured to said central portion; means pivotally supporting one of said legs inside said support below said aperture, the other of said legs being disposable outside said wall to support said central portion when said central portion extends through said aperture; and means on the lower end of said other of said legs for closing said aperture when said member is retracted within said support.

9. In a stool: a support having a wall provided with an aperture; a seat on the top of the support; a generally U-shaped member movable through said aperture, said member having a central foot portion, a first supporting leg rigidly secured to said foot portion and disposed within said support, and a second supporting leg secured to said foot portion and adapted to be disposed externally of said support when said foot portion projects outwardly from said aperture; means pivotally supporting said inner leg within said support below said aperture; said aperture being

sufficiently large to permit said foot portion to pass therethrough upon swinging of said foot portion with said inner leg about said pivotal support.
